FIG. 2.

UNITED STATES PATENT OFFICE.

JOSEPH W. GRAY, OF FOWLER, INDIANA.

REPEATER FOR TELEGRAPH-LINES.

SPECIFICATION forming part of Letters Patent No. 700,037, dated May 18, 1902.

Application filed November 22, 1901. Serial No. 83,295. (No model.)

To all whom it may concern:

Be it known that I, JOSEPH W. GRAY, a citizen of the United States, residing at Fowler, in the county of Benton and State of Indiana, 5 have invented new and useful Improvements in Repeaters for Telegraph-Lines, of which the following is a specification.

My invention relates to repeaters for telegraph-lines; and the object of the same is to 10 construct a repeater including two relays in the same circuit constructed and arranged in such a manner that they will not interfere with one another. The novel construction by 15 which this object is attained is fully described in this specification and claimed, and illustrated in the accompanying drawings, forming a part thereof, in which—

Figure 1 is a diagrammatic plan of the arrangement of my apparatus, illustrating the 20 principle employed. Fig. 2 is a diagrammatic plan of a second arrangement of apparatus as actually used in an operating system.

The principle of my device will first be explained by referring to Fig. 1, after which the 25 system shown in Fig. 2 will be taken up.

As shown in Fig. 1, I employ two relays—a high-resistance relay R and a low-resistance relay R'. Suppose the coils 1 of the relay R have a resistance ten times greater than the 30 coils 2 of the relay R'. The relay R is provided with a spring 3, adjusted to respond to a weak current through the coils 1, and the relay R' is provided with a spring 4, adjusted to respond to a strong current through the 35 coils 2. A battery B is connected to the relay R' by a conductor 5 and to a key K' by a conductor 6. The key K' is connected to a resistance-coil 7 by a conductor 8. The resistance of the coil 7 is approximately equal 40 to the resistance of the coils of the relay R'. The coil 7 is also connected to the coils 1 of the relay R by a conductor 9. The opposite end of the coil 7 is connected by a conductor 10 to a key K, which key is connected to the 45 relays R and R' by conductors 11 and 12, respectively.

The operation of the device above set forth can now be described. When the key K' is closed and the key K is open, a circuit would 50 be completed via battery B, relay R', conductor 12, relay R, conductors 9 and 8, key K', back to battery. If the key K remains open and

the key K' be operated, the relay R will respond, since its spring 1 is adjusted to work with a small current; but the relay R' will 55 remain inoperative, since its spring 2 is adjusted to respond only to a heavy current. Now if both keys K and K' be closed two circuits will be completed—the first via the relays R and R', the same as before, and the 60 second via the relay R', conductor 12, key K, resistance-coil 7, conductor 8, and thence to battery B. The current will be divided between the two circuits in the inverse proportion to the resistance in them. Therefore the 65 first will receive one-sixth and the second five-sixths of the whole, disregarding the difference in resistance of the linear conductors in the two circuits. The relay R' will then respond to the operation of either key, provided the other remains closed. If now the key K' be opened, then there is no circuit and neither relay will respond to the operation of key K.

In fitting up a station for regular work I 75 prefer to use a more complete arrangement of apparatus, such as is shown in Fig. 2. In this arrangement there are two high-resistance relays T' and T², having armatures 13 and springs 14, adjusted to respond to a small 80 current. Resistance-coils 15 and 16 are located adjacent to relays T' and T², respectively, and provided with contact-points 15^a and 16^a, respectively, located to be engaged by the armatures 13 of the relays to complete 85 a circuit through them when a circuit is completed through the relay-coils. In addition to the two relays T' T², I use two low-resistance relays E' E², placed near keys K' K², respectively, and sounders S' S². The latter 90 are connected in local circuits with batteries L' and L². The keys K' and K² are situated at widely-separated stations, while the relays T' and T² are at an intermediate station. The 95 resistance of each of the relays E' and E² is about one-tenth of that of the relays T' T².

Batteries H' and H² are located near the keys K' and K², respectively, and are connected to said keys by conductors 17 and to resistance-coils 16 and 15 by conductors 18. 100 The keys K' and K² are also connected to relays E' and E² by conductors 19. The relay T' is connected to the armature of the relay T² by a conductor 20 and to the relay E' by

a conductor 21. The relay T² is connected to the armature of relay T' by a conductor 22 and to the relay E² by a conductor 23.

In operation when the key K' is closed a circuit will be completed via battery H', key K', relay E', conductor 21, relay T', conductor 18, and back to battery H'. The closing of this circuit will cause the relay T' to attract its armature and bring it into engagement with the contact-point 15^a, while the relay E' will remain inoperative, owing to there being too much resistance in circuit. Now if key K² be closed a circuit will be completed through the relay T²; but in addition to this a circuit will be completed via battery H², conductor 18, resistance-coil 15, contact-point 15^a, armature 13 of relay T', conductor 22, conductor 23, relay E², conductor 19, key K², back to battery H². The closing of this circuit will operate the relay E², since the current is shunted around the relay T² normally in circuit and gives the relay E² enough current to work it. The key K² can then be operated to operate the relays E² when the key K' is closed, also T² and E'.

By the above arrangement the operator at either station can always tell by means of his local sounder whether his message is being repeated to the distant receiving-station, as this would not be the case unless the circuit including the receiving-station was closed.

In case the key K' was closed the key K² could be operated to operate the relays E', T', and E². From the foregoing it is evident that unless one of the keys K' K² is closed the other cannot be used to repeat.

My repeater is adapted for use on long metallic or grounded lines. By its use the line may be divided up into sections.

I do not wish to be limited as to details of construction and arrangement, as these may be modified in many particulars without departing from the spirit of my invention.

Having thus described my invention, what I claim as new, and desire to secure by Letters Patent, is—

1. In a repeater, the combination of a high-resistance relay, a low-resistance relay, a battery, and a key all connected in circuit, a circuit-breaker and a resistance-coil both in shunt around said high-resistance relay, substantially as described.

2. In a repeater, the combination of a low-resistance relay-coil, a high-resistance relay-coil, a battery and a first key all connected in circuit, a resistance-coil and a circuit-breaker both in shunt around said high-resistance relay, means for operating said circuit-breaker, a second key and a battery all three of the last-mentioned devices included in circuit, substantially as described.

3. In a repeater, the combination of a low-resistance relay-coil, a first key, a battery and a high-resistance relay all connected in circuit, a resistance-coil and a circuit-breaker both connected in a shunt around said high-resistance relay-coil, a local sounder, a battery and a circuit-breaker all three connected in circuit, said circuit-breaker being arranged to be operated by said high-resistance relay-coil, substantially as described. 65 70

4. In a repeater, the combination of a first low-resistance relay-coil, a first key, a battery, and a first high-resistance relay-coil all connected in circuit, a resistance-coil and a first circuit-breaker both connected in a shunt around said high-resistance relay-coil, a local sounder, a battery and a circuit-breaker all connected in circuit, said last-mentioned circuit-breaker being arranged to be operated by said low-resistance relay-coil, a second key, a battery, and a low-resistance relay-coil all four connected in circuit, said second low-resistance relay-coil being arranged to 85 operate said first circuit-breaker, a second circuit-breaker and a resistance-coil both connected in a shunt around said second high-resistance relay-coil, said second circuit-breaker being arranged to be operated by 90 said first high-resistance relay-coil, substantially as described. 80

5. In a repeater, the combination, of a first low-resistance relay-coil, a first key, a battery, and a first high-resistance relay and all four connected in circuit, a local sounder, a battery and a circuit-breaker all three connected in circuit, said circuit-breaker being arranged to be operated by said low-resistance relay-coil, a resistance-coil and a first circuit-breaker 95 all connected in a shunt around said high-resistance relay-coil, a second low-resistance relay-coil, a second high-resistance relay-coil, a second key, and a battery all four connected in circuit, said second high-resistance coil 105 being arranged to operate said first circuit-breaker, a second circuit-breaker, and a resistance-coil both connected in a shunt around said second high-resistance relay-coil, said second circuit-breaker being arranged to be operated by said first high-resistance relay, a local sounder, a battery and a circuit-breaker, said last-mentioned circuit-breaker being arranged to be operated by 110 said second low-resistance relay-coil, substantially as described. 115

In testimony whereof I have hereunto set my hand in presence of two subscribing witnesses.

JOSEPH W. GRAY.
